(CL. D89—1)

To all whom it may concern:

Be it known that we, Joseph M. Majewski, Jr., and Henry J. Talge, citizens of the United States, residing at Kansas City, in the county of Jackson and State of Missouri, have invented a new, original, and ornamental Design for an Ice Crusher, of which the following is a specification, reference being had to the accompanying drawing, forming part thereof, in which

Fig. 1 is a side elevational view of an ice crusher showing our new design,

Fig. 2 is a front elevational view thereof, and
Fig. 3 is a top plan view.

We claim:

The ornamental design for an ice crusher,
substantially as shown.

JOSEPH M. MAJEWSKI, JR.
HENRY J. TALGE.
